UNITED STATES PATENT OFFICE.

WILLIAM B. HOUGH, OF CHICAGO, ILLINOIS, ASSIGNOR TO PATENTED DEVICES COMPANY, OF PORTLAND, MAINE, A CORPORATION OF MAINE.

REINFORCEMENT FOR CONCRETE CONSTRUCTION.

1,172,026.

Specification of Letters Patent.

Patented Feb. 15, 1916.

Application filed March 29, 1912. Serial No. 687,175.

To all whom it may concern:

Be it known that I, WILLIAM B. HOUGH, a citizen of the United States, and resident of Chicago, in the county of Cook and State of Illinois, have invented certain new and useful Improvements in Reinforcements for Concrete Construction, of which the following is a description, reference being had to the accompanying drawings, which form a part of my specification.

My invention relates more especially to metal reinforcements for concrete construction, such as columns, piles, and the like, whereby an efficient and at the same time inexpensive binder or device is produced which will greatly increase the strength of a column or upright, as will be readily understood from the description herein.

The object of the invention is to produce a reinforcement or device composed of as few parts as would be consistent with practical construction capable of being readily assembled, and which will permit of being folded or put into a collapsed condition for the purpose of shipment or storage, while at the same time permitting it to be quickly extended or set up in proper position without the necessity of special fitting.

The invention is more especially intended for use in connection with the usual forms employed to receive or incase the cement or concrete in which the reinforcement is to be embedded as will be thoroughly understood from the following detailed description of the drawings, wherein:

Figure 1 is a perspective view of my improved reinforcement shown in its assembled and "set up" condition, being partially embedded in concrete formed in the nature of an upright or column. Fig. 2 is a detail view of a portion of the spacer-blank or vertical member, showing the manner of forming the retaining sockets or openings before the blank has been bent into the desired shape. Fig. 3 is a cross sectional view taken on the line *a*—*b* of Fig. 2, with the spacer-blank bent at its longitudinal center line so as to bring the socket or opening at an outer edge where it is to receive the round or coil of the encircling member of the reinforcement. Fig. 4 is a similar view, illustrating the spacer or vertical member in a slightly expanded condition after the rounds or coils of the encircling element or means have all been inserted in place. Fig. 5 is a detail

view of a portion of a spacer-blank shown in elevation, illustrating a modified form of my invention. Fig. 6 is a perspective view of the modified form, showing the spacer-blank or upright bent into proper shape, with a portion of a round or coil of the encircling member or means, also of modified form, shown seated in place. Fig. 7 is a detail view of a portion of a spacer-blank showing another modified form of my invention. Fig. 8 is a perspective view of the assembled reinforcement employing the modified form of spacer-blank or upright shown in Fig. 7; the reinforcement being shown embedded in a concrete column or upright.

For the purpose of illustrating my invention when in its assembled or "set up" condition and the manner of its application, I show the same, in Fig. 1, partially embedded in concrete.

The invention consists of a suitable number of spacing members or elements 10, circumferentially arranged in a vertical position as clearly shown in Fig. 1. The spacing members 10 are preferably formed of strips of flat sheet metal, as illustrated in Fig. 2, provided with suitably spaced cut-out portions 11, arranged preferably at the longitudinal center line of the spacing members. As the spacing members, in the preferred form of my invention, are intended to receive the successive turns or coils of a continuous encircling member, I prefer to arrange the slots 11 at a slight incline, as shown in Fig. 2, so that the slots may coincide with the slight incline of the respective turns or coils of the encircling member; the slots 11, of course, corresponding in number with the number of turns or coils in the encircling element.

The cut-out portions or slots 11 are intended to form pockets or sockets for the turns or coils of the continuous encircling spiral member 12, or for encircling means, when the members 10 have been bent into proper form, which is accomplished by preferably bending the same substantially at the longitudinal center line thereof, as indicated by the dotted line *c* in Fig. 2, or along a line that extends through the longitudinally arranged series of openings, thus providing two portions or legs *a*—*b* arranged perpendicular or at an angle to the encircling means or member 12, as clearly shown in Figs. 1 and 3.

It will be seen that the bending of the spacing means or members in the manner described will bring the cut-out portions or openings at the vertex or bent edge of the 5 spacing means, and provide suitable sockets for the reception of the respective turns or coils of the encircling element 12 or portions of the encircling means.

The slot or opening 11, in the construction illustrated in Figs. 1 to 4, has its ends depended downwardly and slightly presented toward each other, as more clearly shown in Fig. 2, thus providing an intermediate projecting portion 11^a the opposite 10 upper edges whereof slightly extend into the slot, as clearly shown in Fig. 2. The ends of the slot or opening which extend slightly beneath the upper edges of the intermediate portion or tongue 11^a form the sockets or 15 "seats" for the coils or turns of the encircling means or member 12 when the upright or spacing members have been bent into proper form, as shown in Fig. 3.

The intermediate portions 11^a of the respective slots, it will be seen, will prevent the accidental removal of the coils of the encircling means or member. After all of the coils or turns of the encircling member have been 20 properly placed in their respective slots, the 25 vertical or spacing members 10 are preferably slightly expanded as shown in Fig. 4. By thus expanding the members, the coils or turns of the encircling member will be forced into the ends of the opening so as to 30 come slightly beneath the extended corners 35 of the intermediate or lip portion 11^a and be firmly held in place. The vertical or spacing members 10 will properly maintain the different coils or turns of the encircling 40 means in the proper separated or spaced relation to each other.

The encircling means 12 in Figs. 1 to 4, is shown in the nature of a continuous or spiral wire, which is adapted to resist the 45 lateral or transverse stresses that occur in the columns or upright members of the concrete construction. The encircling means may, however, be made in various forms and of any desired length; for example, in Fig. 50 6, the encircling means is shown in the nature of a flat member or band 12^a, rectangular in cross section. When this form of encircling member is employed, the spacing members 10 are provided with the substantially 55 rectangular cut-out portions or slots 11^b, see Fig. 5, the lower corners whereof are extended downwardly so as to provide the intermediate portion or tongue 11^c. The upper corners of the intermediate portion 60 11^c preferably extend slightly into the cut-out portion as clearly shown in Fig. 5.

When the coils or turns of the encircling member 12^a have been inserted in their respective slots in vertical member or spacer 65 10, the coils or turns will be seated in the

extended lower portions of the slot, as clearly shown in Fig. 6. The spacing member 10 may then be slightly expanded, as shown in Fig. 4, which will bring the extended upper corners of intermediate portion 70 11^c into frictional engagement with the encircling means, thereby causing the coils or turns of the encircling element 12^a to be firmly gripped or clamped against accidental removal.

Where the encircling member is of considerable diameter, I prefer to employ a number of spacing members so as to properly maintain the coils or turns in the desired spaced relation throughout their 80 length.

The spacing members 10 not only act as spacers for the different coils or turns of the encircling element 12, when the reinforcement is in "set up" position, but the 85 spacers also provide means whereby the encircling element may be readily put into a condensed or collapsed condition. It is evident from the construction shown and described, that the spacing members may be 90 readily slid along the coils or turns of the encircling member, especially when the legs or sides of the spacers are slightly contracted, so that the spacing members, where more than two are employed, may be assembled or 95 brought together at two points diametrically opposite each other. This will permit the assembled spacing members on opposite sides of the encircling element to be moved or forced in opposite directions, thereby 100 bringing the parts of the reinforcement into a collapsed condition with the coils or turns of the encircling element extending almost parallel with the spacers. By putting the reinforcement into the compact form just 105 described, it may be easily handled and at the same time occupy considerably less space than would be the case if it were necessary to maintain the reinforcement in its extended or "set up" condition. To place 110 the reinforcement into its extended or "set up" condition, it is merely necessary to move the oppositely disposed spacing members in a direction opposite to that when collapsing the reinforcement, which will bring the 115 parts into proper position, as shown in Fig. 1.

In Figs. 7 and 8, I show still another modified form of my invention, wherein the upright or spacing members are provided 120 with slots in their outer longitudinal edges instead of in the bent edge or vertex thereof. The slots shown in Figs. 7 and 8 are substantially similar to those shown in Fig. 1.

The slots 11^a extend into the blank from the opposite longitudinal edges, with the respective slots at the opposite sides of the blank arranged substantially in the same plane with each other, and have their inner ends curved downwardly similar to the man- 125 130

ner shown in Fig. 2; the inner ends of the slots curve slightly toward the outer edge of the blank, so as to provide the portion or tongue 11°, beneath which the rounds or 5 coils of the encircling means will be seated.

After all the coils or turns of the encircling means have been placed in their respective slots, the spacers 10, shown in Figs. 7 and 8, are expanded. This will maintain the 10 coils or turns of the encircling means within the slots at a point beneath the tongues 11°, where they will be firmly gripped.

In Fig. 8, I illustrate another method of 15 assembling the various elements of my improved reinforcement, whereby the spacers are arranged outside of the encircling means, so that the bent or nose portion of the spacers will act as a spacing means or gage to maintain the proper relative position of the encircling means to the outside casing or form.

In practice, the concrete surrounds the different members or elements of the reinforcement on all sides and fills in between the coils or turns of the encircling means and 25 also fills in the openings or slots adjacent the rounds or coils as shown in Fig. 1, so that the reinforcing device and the concrete will be firmly united.

The different members of the reinforcement 30 may be of any desired length and the encircling means may be of any desired size or width.

I have shown and described various forms 35 of my invention as well as different methods of employing the same, but it is apparent that other alterations and modifications may be made without, however, departing from the spirit of my invention. I do not wish, therefore, to limit myself to the specific 40 forms shown and described, but

What I claim as my invention, and wish to secure by Letters Patent, is:—

1. A reinforcement for concrete construction, comprising encircling means, and a plu-

rality of spacers arranged lengthwise of the 45 encircling means, the spacers consisting of sheet metal blanks bent longitudinally so as to provide angularly expansible members, with the portion of said members adapted to contact with the encircling means being provided with transversely extending slots 50 arranged in longitudinal series and of width adapted to permit insertion of the encircling means laterally, the ends of the slots arranged to receive the encircling means being 55 extended downwardly and slightly rearwardly so as to provide an intermediate portion having upwardly presented lips extending into said slots so as to provide restrictions at points where the slots are disposed 60 downwardly, said lips being adapted to grip said encircling means and prevent lateral displacement thereof when said members are expanded.

2. In a reinforcement for concrete construction provided with an encircling element, spacing means comprising blanks of sheet metal bent longitudinally so as to provide angularly expansible members, said members being provided with transversely 70 disposed slots of width adapted to permit lateral insertion of an encircling element, said slots being arranged in longitudinal series with the ends of the slots being extended downwardly and slightly under the 75 main portion of the slots so as to provide upwardly presented portions having corners or lips adapted to form restrictions at points where the slots extend downwardly and thereby provide gripping portions, whereby 80 an element inserted in said slots will be held against lateral displacement when said members have been expanded.
